UNITED STATES PATENT OFFICE.

GIOVANNI AGATI, OF SAN FRANCISCO, CALIFORNIA.

COMBINED CHAIR AND HIGH CHAIR.

1,243,913.

Specification of Letters Patent. Patented Oct. 23, 1917.

Application filed January 6, 1917. Serial No. 141,004.

To all whom it may concern:

Be it known that I, GIOVANNI AGATI, a citizen of the United States, residing at San Francisco, in the county of San Francisco and State of California, have invented certain new and useful Improvements in Combined Chairs and High Chairs, of which the following is a specification.

My invention relates to new and useful improvements in chairs and has for its primary object the provision of a combined chair and high chair so constructed that normally it will have the appearance of an ordinary dining chair and may be used as such, but so arranged that it may be readily converted into a high chair, when desired.

A still further object of my invention consists in constructing a chair of the above described character in which all of the high chair structure is connected to the seat box and seat of the chair in such a manner that, under ordinary conditions, the high chair structure is entirely supported beneath the seat and inclosed within the seat box where it will be out of sight and where it will not in any way interfere with the ordinary use of the chair by an adult.

A still further object of my invention consists in hinging the seat proper of the chair to the seat box in such a manner that it may be swung upwardly against the back of the chair so that a supplemental seat having arms and a tray may be swung into active position to permit use of the device as a high chair.

Another object which I have in view is the provision of means for so connecting the supplemental seat, its arms and tray to the seat box, and main seat that when the device is arranged for service as a high chair all parts will be firmly braced and held in place.

Another object which I have in view is the mounting of the tray upon the arms of the high chair seat in such a manner that it may be swung upwardly and forwardly away from the lower face of the main seat which, when the device is employed as a high chair, forms the back of the child's seat in order to

provide ample space for placing the child in the chair.

With these and other objects in view, my invention will be more fully described, illustrated in the accompanying drawings, and then specifically pointed out in the claim which is attached to and forms a part of this application.

In the drawings:

Fig. 1 is a perspective view of my improved chair arranged to receive a child and serve as a high chair;

Fig. 2 is a central vertical sectional view of the chair arranged for ordinary use by an adult;

Fig. 3 is a view corresponding to Fig. 2, but showing the main seat of the chair in elevated position and illustrating the supplemental chair structure in elevation instead of in section;

Fig. 4 is a view corresponding to Fig. 3, showing the supplemental chair structure in partially raised position;

Fig. 5 is a front elevation of the chair when arranged for a child's use;

Fig. 6 is a fragmentary perspective view, illustrating the manner in which the main chair seat is hinged to the body of the chair.

Corresponding and like parts are referred to in the following description and indicated in all the views of the drawings by the same reference characters.

The sole difference in construction between the chair proper of my invention and that of the ordinary dining chair is that the seat is hinged to the chair body. I will, therefore, explain in a general way, the construction of the chair proper and then more particularly the construction of the supplemental or connected parts which coöperate to form the supplemental seat having arms and a tray and adapted to be supported by the chair in elevated position for use by a child. The chair proper includes the front legs 10 and rear legs 11 connected by the usual seat box forming stretchers 12 and adjacent their lower ends by the usual brace rungs 13. The rear legs 11 are extended to form the sides 14 of the chair back, being connected at spaced intervals above the seat 100

box by the usual stretchers 15. At this point it should be noted that the rear stretcher 12 projects at its upper edge somewhat above the level of the upper edges of 5 the remaining seat box stretchers and that all of these stretchers, as well as the rungs, preferably have mortise and tenon connection with the legs of the chair. The seat proper 16 of the chair is hinged to the chair 10 body by hinges, indicated as a whole by the numeral 17 so that it may normally rest upon the upper faces of the side and front stretchers 12 and upper ends of the front legs 10 or may be swung upwardly and 15 rearwardly to rest against the back forming portions 14 of the rear legs and against one of the back stretchers 15. This seat is constructed to slightly overhang the seat box, as is usual, and in order that it 20 may do this and still be hinged to the seat box its rear corners are cut-away, as shown at 18, so that its rear edge, which is disposed in close proximity to the forward face of the rear seat box stretcher 12, may swing 25 downwardly between the side seat box stretchers 12. Each hinge 17 includes a hinge member 19 of strip metal of suitable weight secured to the inner face of one of the side seat box stretchers 12 by screws 20 30 or other suitable fastening means and extending upwardly and rearwardly along said stretcher is a free hinge ear 21 projecting above the upper face of the stretcher and in proximity to the adjacent rear leg of 35 the chair. Each hinge further includes a hinge member 22 of strip metal, secured by screws 23 or other suitable fastening means to the lower face of the chair seat proper 16 and formed at one end with an upbent 40 hinge ear 24 which projects into a slot 25 formed in the chair seat to receive it and the hinge ear 21, a pintle pin 26 pivotally connecting these ears. By this arrangement, the pivoted portions proper of the 45 hinges are seated in the slots of the chair seat and any danger of injury to wearing apparel and the like, through catching upon the hinges, is avoided. Furthermore, when the chair is in closed position, the hinges 50 are completely hidden from view, as will be readily appreciated by reference to Fig. 2 of the drawings.

Substantially L-shaped hinge plates 27 are secured by one arm to the under face 55 of the chair seat 16 adjacent each side and in opposed relation to each other so that their free arms project forwardly at right angles to the chair seat to swingingly support a supplemental seat 28. This supplemental seat 28, when in raised position, as 60 shown in Fig. 1 of the drawings, engages at its rear edge against the main seat 16 and the free arms of the hinge plates 27 engage in cut-away portions 29 formed in the sides of the supplemental seat 28. Pivot

pins 30 connect the supplemental seat 28 to the end portions of the free arms of the hinge plates 27 at such a distance from the rear edge of the supplemental seat 28 that when the supplemental seat is folded back 70 against the lower face of the main seat, its free edge will engage against the main seat, while its edge adjacent the hinges is spaced therefrom, as fully shown in Figs. 2 and 3 of the drawings. Supporting blocks 31 75 are secured to the under face of the main seat 16 adjacent each of the hinge brackets 27 to engage and support the rear portion of the supplemental seat 28 when it is in fully raised position, as shown in Fig. 1. 80

Brace plates 32 are secured to the under face of the supplemental seat 28 adjacent its forward edge and project beyond the sides of such seat and at their free ends have upwardly directed ears or terminals 33. Arm 35 supporting standards 34 are pivoted at their lower ends between the terminals 33 and sides of the supplemental seat 28 by pivot pins 35 which also pass through the upper ends of seat supporting braces 36 which bear against 90 the outer faces of the terminals 33. These braces 36 are formed of metal of suitable weight and are bowed outwardly at points slightly below the supplemental seat 35 so that their lower or free ends will slidably 95 engage against the inner faces of the side stretchers 12 of the chair body. The lower ends of these braces are correspondingly slotted, each brace being formed with a longitudinal slot 37 terminating adjacent the 100 end of the brace with a laterally and upwardly directed extension or pin receiving seat 38, and guide and supporting pins 39 project through these slots and are anchored in the side stretchers 12. These slots are so 105 formed and the supporting and guide pins 39 are so located as to in no way interfere with the swinging of the supplemental seat 28 to its raised or lowered position. However, when the supplemental seat is raised, 110 the side braces 36 may be sprung somewhat to bring the lower ends of the notches at the pins and the lower ends of the braces may then be sprung rearwardly and released so that the pins will seat in the upwardly directed terminals 38 of the notches in order 115 that the braces may serve to readily support the front portion of the supplemental seat 28.

Each of the braces is formed with an inwardly directed extension 40 projecting at right angles to the plane of the brace and having a forwardly directed ear 41 which, in raised position of the supplemental seat 28, is disposed substantially level with the 125 upper edges of the front and side stretchers 12 of the chair body. A foot rest 42 is hinged to the upper rear edge portion of the front stretcher 12, as shown at 43, in such a manner that it may be swung up- 130

wardly in vertical alinement with the stretcher, as shown in Fig. 4, or downwardly to lie against the inner face of the stretcher, as shown in Fig. 2. When the supplemental seat is in raised position, it will be clear that this foot rest may be swung to the position shown in Fig. 1 to bear upon the supporting ears 41 and provide a suitable foot rest. Hinge brackets 44 are secured to the lower face of the seat proper 16 adjacent either side edge and near the front thereof, being spaced from each other a distance equal to the width of the supplemental seat 28 and each of these hinge plates is formed with a pair of outwardly directed hinge ears 45 adapted to receive between them the rear end of an arm 46, these arms being connected to the ears by hinge pins 47. These arms form arms for the child's seat and project a considerable distance beyond the forward edge of the supplemental seat 28 and the upper faces of the arms intermediate their length are notched to receive the bight portion of U-shaped hinge stirrups 48, the sides of which project below the arms to straddle the upper ends of the arm supporting standards 34 which are pivoted between them by hinge pins 49. By this means, the arms and supplemental seat are connected to swing in unison. It should be noted that the ends of the arms are connected to the hinge brackets 44 at such a distance from the main seat 16 as will permit them to lie substantially parallel with the main seat when the supplemental or child's chair is folded against it in order to provide space for the arm supporting standards 34 between them and the main seat.

Hinge plates 50 secured to the inner faces of the arms 46 at their free ends have hinge ears which project forwardly and downwardly beyond the ends of the arms and hinge pins 51 are passed through these ears and through the ears of L-shaped hinge brackets 52 secured to the under face of a tray 53 adjacent its forward edge so that the tray may rest upon the arms, as shown in Fig. 1 or may be swung forwardly in front of the free ends of the arms, as preferred. This tray includes a body 54 surrounded by an upstanding marginal wall 55 which will serve to prevent displacement of dishes, toys or other articles placed on it. The tray, at one side and adjacent its rear edge, carries an L-shaped bracket 56, the depending arm of which is provided with an opening to receive a spring pressed bolt 57 mounted in a housing 58 secured to the outer face of the adjacent arm and having an operating finger 59. This latch serves to lock the tray in its normal position, shown in Fig. 1, so that it may not be swung outwardly by a child occupying the chair.

In describing the manner of employing the chair, it will first be assumed that the parts are in the condition shown in Fig. 2 of the drawings, under which circumstances, the chair is adapted for use by an adult, all of the high chair structure or supplemental parts being supported within the chair box and held against displacement by a supporting bar 60, preferably formed of metal and extending transversely across the lower portion of the chair box, being secured at its ends to the lower edges of the side stretchers 12. When the chair is to be used as a high chair, the seat proper 16 is swung upwardly to the position shown in Fig. 3 and the foot rest 42 is also swung to the position there shown. With the parts in this position, the lower edge of the tray is grasped and the arms and supplemental seat 28 are swung upwardly in the manner which will be clearly understood by reference to Fig. 4, the braces 36 first riding downwardly upon the pins and as the parts pass dead center riding upwardly along the pins until the pins are located adjacent the lower ends of the slots. The braces are then sprung to seat the pins in the ends 38 of the slots so that the supplemental seat, together with its arms and tray, will be firmly supported in place, the braces not only serving as a support for these parts but also holding the main seat 16, which forms the back of the supplemental seat 28, firmly against the back of the chair proper. The foot rest 42 is then swung downwardly to the position shown in Fig. 1 when the chair is ready for use by a child. By releasing the latch bolt 57, the tray may be swung forwardly in order to provide ample room for placing the child in its seat, after which the tray may be swung back and locked so that it will prevent the child from falling from the seat and so that it may serve to hold dishes, toys or other articles. Obviously, the parts may be returned to normal position so that the chair may be used by an adult by merely reversing the operation above described.

Having thus described the invention, what is claimed as new is:

A combined chair and high chair including front and rear legs and stretchers connecting them providing a chair body having a seat box and back, a main seat hinged to the seat box and adapted to rest thereon or to be swung upwardly and rearwardly against the chair back, a supplemental seat hinged to the under face of the first seat and capable of being swung outwardly at substantially right angles thereto when the first seat rests against the back, supporting braces pivoted to the sides of the supplemental seat near its free forward edge and formed at their opposite ends with guide slots having offset anchoring terminals, pins carried by

adjacent stretchers of the seat box engaging in the slots and adapted to seat in the terminals thereof when the supplemental seat is raised to support such seat, inwardly directed brackets carried by the braces, and a foot rest hinged to the forward stretcher of the seat box and adapted to rest upon the

brackets whereby as long as pressure is exerted upon the foot rest the braces will be held against such movement as could free 10 the pins from the anchoring terminals of their slots.

In testimony whereof I affix my signature.
GIOVANNI AGATI. [L.S.]
